US00D987680S

(12) **United States Design Patent** (10) **Patent No.:** **US D987,680 S**
(45) **Date of Patent:** **** May 30, 2023**

(54) **DISPLAY SCREEN WITH ICON**

(71) Applicant: **Google LLC**, Mountain View, CA (US)

(72) Inventor: **Sehee Lee**, Brooklyn, NY (US)

(73) Assignee: **GOOGLE LLC**, Mountain View, CA (US)

(**) Term: **15 Years**

(21) Appl. No.: **29/784,806**

(22) Filed: **May 21, 2021**

Related U.S. Application Data

(63) Continuation of application No. 29/784,147, filed on May 18, 2021, now Pat. No. Des. 960,199, which is a continuation of application No. 29/783,980, filed on May 17, 2021, now Pat. No. Des. 948,571, which is a continuation of application No. 29/783,755, filed on May 14, 2021, now abandoned, which is a continuation of application No. 29/783,532, filed on May 13, 2021, now Pat. No. Des. 969,861, which is a continuation of application No. 29/783,060, filed on May 11, 2021, now Pat. No. Des. 969,860, which is a continuation of application No. 29/761,088, filed on Dec. 7, 2020, now abandoned, which is a continuation of application No. 29/739,070, filed on Jun. 22, 2020, now Pat. No. Des. 910,713, which is a continuation of application No. 29/716,373, filed on Dec. 9, 2019, now abandoned, which is a continuation of application No. 29/695,508, filed on Jun. 19, 2019, now Pat. No. Des. 878,417, which is a continuation of application No. 29/643,547, filed on Apr. 10, 2018, now abandoned.

CLAIM

The ornamental design for a display screen with icon, as shown and described.

DESCRIPTION

The sole FIGURE is a front view of a display screen with icon showing the new design.

The broken lines of uneven length show the display screen and form no part of the claimed design.

1 Claim, 1 Drawing Sheet
